TELEPHONE HAND SET SUPPORT

Max Fechter and Saul Fechter, New York, N. Y.

Application July 13, 1953, Serial No. 25,896

Term of patent 14 years

(Cl. D26—14)

To all whom it may concern:

Be it known that we, Max Fechter and Saul Fechter, both citizens of the United States, and residing, respectively, at New York city, in the county and State of New York, and at New York city, in the county of the Bronx, and State of New York, have invented a new, original, and ornamental Design for a Telephone Hand Set Support, of which the following is a specification; reference being had to the accompanying drawing, forming a part thereof.

Fig. 1 is a front elevational view of a telephone hand set support, showing our new design.

Fig. 2 is a top plan view thereof.

Fig. 3 is a side view thereof, parts of the standard and base being broken away.

Fig. 4 is a sectional view taken on line 4—4 of Fig. 1.

Fig. 5 is a view similar to Fig. 1 with the standard and base broken away, and showing the tele-

phone hand set resting in the cradle of the support, for the purpose of illustration only.

The dominant features of the design reside in the portions shown in full lines.

We claim:

The ornamental design for a telephone hand set support, substantially as shown, and described.

MAX FECHTER.
SAUL FECHTER.
